UNITED STATES PATENT OFFICE.

HORACE K. JONES, OF HARTFORD, ASSIGNOR TO THE RUSSELL & ERWIN MANUFACTURING COMPANY, OF NEW BRITAIN, CONNECTICUT.

INTERMITTENT ROLL FEED MECHANISM.

SPECIFICATION forming part of Letters Patent No. 314,451, dated March 24, 1885.

Application filed August 11, 1884. (No model.)

To all whom it may concern:

Be it known that I, HORACE K. JONES, of Hartford, in the county of Hartford and State of Connecticut, have invented certain new and 5 useful Improvements in Intermittent Roll Feed Mechanism for Delivering Metal Rods, Wire, or Plates, &c.; and I do hereby declare that the following specification, taken in connection with the drawings furnished and forming a part of the same, is a clear, true, and complete description of my invention.

My said improvements relate to what is known as "friction feeding mechanism," as distinguished from the well-known pawl-and-ratchet feed, and although they are applicable to any variety of metal-working machinery in which rolls are employed for intermittently feeding metal bars, rods, wire, or plates to be worked into various forms, I have specially organized them for use in feeding wire to nail and screw blank heading machines; and it is in those or analogous connections that they have their prime value. It is well known that wire intentionally of the same 25 gage varies not only as between one coil and another, but also as between the two ends of the same coil of wire, and that wire of any given size must be fed to a lesser extent to form a head of a given size than smaller wire 30 for forming a head of the same size, and therefore it is important, if uniformity in heads is to be obtained, that the feeding mechanism should not only be capable of variation, but also that any desired variation may be made 35 easily and promptly and without stopping the machine. Heretofore variations in friction feeding mechanism of the class referred to have only been provided for by the use of a radially-slotted crank-plate and a pitman 40 having a pivot-bolt radially adjustable in the crank-plate slot, and although a slotted crank-plate is preferably employed by me for making radical variations, as when the machine is at rest, an ordinary crank can be used, be- 45 cause I provide as a novel feature means for making both radical and nice adjustments without stopping the machine. So far as my knowledge extends, I am the first to organize with friction feeding mechanism means where-

by either a radical or a nice adjustment, or 50 both, can be practically effected while the mechanism is in motion, and the main feature of my invention involves the combination, with the friction-shoe block and its lever, of an adjusting-screw by which variations in 55 feed may be readily made while the machine is in motion, however said lever may be vibrated. I employ the usual friction-disk and a pivoted block on a swinging arm or lever, which is connected by a pitman to a crank- 60 plate, or it may be operated by a cam; but instead of having, as heretofore, no adjustable connection between said block and the mechanism which vibrates the lever or arm on which said block is mounted, I provide said block 65 with a hand-screw tapped therein. When a pitman is employed, it is flexibly connected to a nut which is fitted to said hand-screw, so that by turning said screw the point of connection with the pitman will be moved nearer 70 to or farther from the arm or lever on which the pivoted block is mounted, and thus cause said arm to be variably vibrated and to correspondingly vary the extent of intermittent 75 rotation of the friction-disk and of the feeding-rolls, one of which is, as usual, mounted upon the same shaft which carries the friction-disk. When a pitman is not employed, and the friction-block arm or lever is vibrated by a cam and a spring or weight, the adjusting- 80 screw not only serves for nice adjustments, but also for radical adjustments, either or both of which can be promptly and readily made without stopping the mechanism.

To more particularly describe my invention, 85 I will refer to the accompanying two sheets of drawings, in which—

Figure 1, Sheet 1, is a side view of feeding mechanism embodying my improvements in connection with a slotted crank-plate and pitman. Fig. 2 is a top view of the same. Figs. 3 and 4 are respectively side and top views of similar mechanism, but differently organized. Figs. 5 and 6, Sheet 2, are respectively side and top views of feeding mechanism embodying the main feature of my invention in connection with a cam and spring for vibrating the friction-block arm. Fig. 7 is a side view

of feeding mechanism in which no separate shoe is employed.

The feed-rolls A are provided with clamp-screws *a*, as heretofore, for enabling the rolls 5 to properly pinch or engage with the interposed rods, wire, or plates to be fed by them, and, as heretofore, the lower roll is mounted upon the shaft *b*, which has keyed thereon at one end the friction-disk *c*, having a smooth, 10 plain periphery, against which the friction-shoe *d* engages, this latter being loosely jointed to the front end of a block, *e*, which is freely pivoted between two arms, which in turn are pivotally mounted upon the shaft *b*, with the 15 friction-disk located between them, all substantially as heretofore, the said arms constituting a lever, *f*.

The slotted crank-plate B is mounted upon a shaft geared to any revolving portion of the 20 machine with which the feed-rolls are to be used, and the lever *f*, shoe-block *e*, and friction-shoe are vibrated in a vertical plane by said crank-plate, which has heretofore been so connected with the lever or arm *f* by means 25 of a rod or pitman, *g*, that variations in the vibratory movement of said lever could only be effected by moving the pitman pivot-bolt *g* toward or from either end of the radial slot in the crank-plate, and this could obviously 30 only be done while the machine was at rest.

As a novel feature in this class of intermittent roller feeding mechanism, I have introduced the hand-screw *C* between the outer end of the pitman *g* and the outer end of the lever 35 or arm *f*. The lower end of this screw is journaled to fit a vertical bearing in the shoe-block *e*, and has a nut, *h*, at its lower end, by which the screw and block are firmly united, while leaving the screw free to be rotated in 40 its bearing. A nut, *i*, is fitted to the screw, and has two ears, between which the outer end of the pitman *g* is pivoted, thus enabling the crank-plate to vibrate the lever *f* as if the latter were directly pivoted to the end of the pit- 45 man.

For limiting the vibration of the shoe-block during the downward movement of the lever *f*, an abutting-screw, *k*, is tapped through an upwardly-projecting portion of said lever at 50 its outer end, so that the inner end of said screw *k* will serve as a variable abutment or stop for limiting the rearwardly vibratory movement of the hand-screw.

As thus far described the mechanism is organized for co-operation with machines like the well-known cut-wire-nail machines, and also with ordinary heading-machines.

When organized for co-operating with presses in which the slotted crank-plate B is usually 60 located above the feed-rolls, the shoe-block *e* is provided with a slotted tail-piece, *e'*, as shown in Figs. 3 and 4, the hand-screw *C* having a similar nut, *i*, to which the lower end of the pitman *g* is pivoted, so that on turning 65 said screw the same variations in feed can be obtained as with the organization previously

described, the abutting-screw *k* being also here applied for operating as before described.

It will be seen as thus far described that for all radical variations in feed the pitman may 70 be adjusted in the slot of the crank-plate, as heretofore, but that all lesser adjustments which are desirable as incidental to variations in the size of wire, &c., can be readily made while the mechanism is in motion by turning 75 the hand-screw in one direction or the other, according to whether a greater or lesser length of rod or wire is to be delivered by the feed-rolls.

It will be obvious that other well-known 80 means for reciprocating the pitman may be substituted for the crank-plate shown without departure from the main feature of my invention, as illustrated on Sheet 2.

In Figs. 5 and 6 it will be seen that the friction-disk *c*, shoe *d*, and pivoted arm *f* on the disk-shaft *b* are all as before described, and also that the shoe-block *e* has a tail-piece, *e'*, as in Figs. 3 and 4. In this organization, however, the revolving cam *B'* performs a 90 portion of the function of the crank-plate *B*, before described, in effecting the lifting or feeding movement, and the spring *l* causes the downward or return movement. The cam *B'* being incapable of adjustment, I here rely 95 upon the adjusting hand-screw *C* to serve also as a stop-screw for limiting the downward or return movement of the shoe-block by abutting with its lower end upon a stationary shelf or bracket, *m*. In this case the hand-screw is 100 tapped into a hole in the tail-piece *e'*, and the latter is longitudinally slotted in the vertical plane of the hand-screw, and has a lateral clamp-screw, *n*, for so clamping the adjusting-screw in its threaded seat as to prevent it from 105 working loose, and said clamp-screw is provided with a handle, by which it can be readily tightened or loosened.

While in most cases it is best to employ with the block *e* a friction-shoe, this latter may 110 be sometimes omitted as a separate device, as for light work, by having the block *e* prolonged or extended, so that its end will operate as a shoe by its contact with the periphery of the friction-disk *c*, the lever *f* and screw *C* 115 being substantially as previously described, as illustrated in Fig. 7.

Having thus described my invention, I claim as new and desire to secure by Letters Patent—

1. The combination, substantially as hereinbefore described, of the feed-rolls, the friction-disk for intermittently driving said rolls, the vibrating arm or lever pivoted on the shaft of said disk, a friction-shoe block pivoted on said arm or lever, and the adjusting-screw 120 mounted in said block for varying the vibratory movement of said arm or lever, and consequently varying the feeding movement of the rolls, as set forth.

2. The combination, substantially as hereinbefore described, of the feed-rolls, the friction-disk, the shoe and its pivoted block, the 130

arm or lever on which said shoe is mounted, means, substantially as described, for vibrating said arm, and the adjusting-screw by which the vibratory movement of said arm or lever is varied and the intermittent movement of the feed-rolls can be correspondingly varied while the machine is in motion.

3. The combination, with the feeding-rolls, the friction-disk, the lever, and the shoe and pivoted block mounted on said lever, of the slotted crank-plate and pitman, and the hand-

screw serving as an adjustable connection between said pitman and pivoted block, substantially as described, whereby variations in the intermittent movement of the feed-rolls 15 can be readily made while the mechanism is in motion.

HORACE K. JONES.
